UNITED STATES PATENT OFFICE

HENRY L. JOHNSON AND BERGER STOCKFLETH, OF NILES, MICHIGAN, ASSIGNEES TO HYDRAULIC PRESSED BEARING COMPANY, OF WILMINGTON, DELAWARE, A CORPORATION OF DELAWARE

TRIMMING MACHINE FOR BEARING SLEEVES

Application filed June 10, 1929. Serial No. 369,689.

This invention relates to improvements in means and methods for trimming or sizing articles such as semi-cylindrical bearing shells or backs for same and has special reference to the trimming or sizing of the outer peripheries of the end flanges of such articles.

The object of the invention is to provide a method and means by which the operation of trimming or sizing such articles can be accomplished very rapidly and automatically and which will require practically no attention other than placing the articles in the machine, the articles being automatically trimmed or sized and ejected.

The invention resides in a machine provided with a rotating drum upon which the shell fits, a belt trained around the drum and moving in consonance therewith, and trimming or sizing means located to operate on the peripheries of the articles as they are carried around by the drum and belt.

In one form, scraping or cutting tools are provided for trimming the edges of the flanges of finished bearing shells. In another form of the device, grinding wheels are provided for grinding or sizing the peripheries of formed up flanged backs for use in making bearing shells.

One important feature of the invention relates to a very simple knock-out device for causing the shells to leave the drum when finished.

Another important feature relates to simple means for adjusting the cutters to properly trim different sized bearing sleeves.

In the form of device for grinding the peripheries of the flanges of the formed backings blanks, the grinding wheel shape is automatically oscillated endwise to cause the wheels to wear down evenly.

Another feature relates to simple drive means associated with the drum for engagement with the shells for positively causing them to be carried around with the drum.

The invention will be more readily understood by reference to the accompanying drawings forming part of this specification and in which:

Fig. 1 is a top plan view of a machine embodying the invention in one form;

Fig. 2 is a vertical section on the line 2—2 of Fig. 1;

Fig. 3 is an enlarged section on the line 3—3 of Fig. 2;

Fig. 4 is a transverse section through the driving drum on the line 4—4 of Fig. 1;

Fig. 5 is a vertical detail section on the line 5—5 of Fig. 3;

Fig. 6 is a fragmentary transverse section on the line 6—6 of Fig. 3;

Fig. 7 is a vertical longitudinal section similar to Fig. 2 but showing a slight modification of the invention;

Fig. 8 is a fragmentary transverse section on the line 8—8 of Fig. 7;

Fig. 9 is a fragmentary vertical section on the line 9—9 of Fig. 7;

Fig. 10 is a perspective view of a flanged half bearing sleeve upon which the machine is intended to operate;

Fig. 11 is a similar view of a rough blank of a sleeve back upon which the form of machine shown in Figs. 7, 8 and 9 is intended to operate.

In said drawings, 1 represents generally a suitable frame consisting of a flat base 2 from which side brackets 3 and 4 rise at each side. The several shafts of the machine are journaled in said brackets. The brackets 4 rise higher than the brackets 3 and at the rear end of the machine carry a transverse shaft 5 which carries a belt pulley 6 for applying power to the machine as by the belt 8. At the opposite end of the machine, a transverse shaft 9 is carried by the brackets 3 and this shaft 9 is driven from the shaft 5 by means of a drive chain 10, the shaft 5 carrying a chain wheel 11 and the shaft 9 a chain wheel 12 for this purpose.

A main operating shaft 13 is carried by the brackets 3 and is located horizontally between the shafts 5 and 9 and vertically in such a relation that one side or stretch of the chain 10 engages a chain wheel 14 secured to the shaft 13 and by which the shaft 13 is rotated in the direction of the arrow 15 on Fig. 2. All of the chain wheels and the drive chain are outside of the frame 1, and the pulley 6 is

located between the brackets 4. Between the brackets 3 there is a belt pulley 16 secured to the driven shaft, and an endless belt 17 is trained around this pulley.

5 At the forward ends of the brackets 4 and above the shaft 13 is arranged another transverse shaft 18. This is an idler shaft and carries a belt pulley 19 around which the belt 17 is trained. The shaft 13 is located between the shafts 9 and 18 and carries a pulley or drum 20 centrally between the side parts of the frame, and the belt 17 is trained around the under side of this drum, as best shown in Fig. 2.

15 At the rear of the frame and in the lower ends of the brackets 4 is mounted another horizontal idler shaft 21 which carries a pulley 22 around which the belt 17 is trained. The shaft 21 is carried in a yoke consisting 20 of vertical side members 23 and a horizontal top member 24. The side members 23 are pivotally mounted at the lower ends of the brackets 4 by pivot bolts 25, thus mounting the yoke to swing back and forth. By means 25 of the yoke, a suitable operating tension can be maintained on the belt 17, means being provided for yieldingly pulling the yoke back. This consists of pull rods 26 which pass through projections 27 rising from the top bar 24 of the yoke and carry springs 28 between an abutment 29 on the frame and adjustable nuts 30 in the rods. The tension on the belt 17 is such that it is yieldingly held against the drum 20.

35 The device upon which the machine is intended to operate is shown in Fig. 11 and is a half cylindrical bearing sleeve, as shown at 31, having end flanges 32. These half sleeves each consists of a harder metal backing 33, usually made of pressed steel and as shown in Fig. 10, and a softer bearing metal lining 34. Likewise, the flanges 32 consist of the harder metal flanges 35 and outer surfaces of which are covered by a layer 36 of the bearing metal.

40 These half cylindrical sleeves are formed by a pressure method in suitable dies, and the outer edges 37 and 38 of the flanges 32 require trimming to properly finish the sleeves.

45 The rear edges 39 of the forward brackets 3 are inclined upwardly and forwardly at an angle of about 45° and serve to support a rigid cross bar 40 which carries suitable cutters for trimming the edges 37-38 at both ends of the sleeve.

50 The drum 20 is of a suitable diameter to fit within the sleeves to be trimmed, and the sleeves are adapted to be held tightly upon the drum, as they pass through, by the belt 17. The belt 17 contacts with the backs of 55 the sleeves between the flanges and assists in driving the sleeves around with the drum.

Two cutters or cutting tools 41 are provided, having V-shaped cutting edges 42, which are best shown in Fig. 3, and are adapted to operate on the edges 37-38 of the

sleeves and scrape or trim them as the sleeves pass through the machine. The tools 41 are mounted in tool holders 43 and are arranged to project radially in relation to the flanges 30 of the backs 31. The holders 43 are mounted on blocks 44 which in turn are mounted on the cross-bar 40. The tools 41 are arranged to be adjustable from and toward the drum 20 for regulating the amount of metal removed and also transversely of the machine for setting accurately spaced, to match the flanges of the sleeves being trimmed. For the transverse adjustments, the tool holders are clamped to the bar 40 by bolts 45 which pass through the two parts 43 and 44 of each holder and through a longitudinal guide slot 46 in the transverse bar 40. Nuts 47 are provided for the lower ends of the bolts 45 and which are beneath the bar 40. Preferably, the bar 40 has a shallow groove 48 for receiving the nuts 47 and preventing them turning around.

55 The lower blocks 44 have transverse guide projections 49 on their lower sides which extend into the slot 46 and long adjusting screws 50 which are arranged longitudinally of the transverse bar 40 entering the slot 46 through threaded holes in the ends of the bar and are provided on their outer ends with knurled heads 51 for ease in turning them. Each screw 50 engages one of the tool hold-

ers. The inner ends of the screws 50 enter into holes provided in the blocks 44, and each is provided with a groove 52 near its inner end to receive the point of a suitable set screw 53 so that the screws 50 can be effective for moving the tool holders in both directions on the transverse bar 40. For adjusting the tools in and out, that is toward and from the flanges to be trimmed, each block 44 is provided on its rear end with an L-shaped projection 54, the free leg 54' of which projects up past the rear end of the upper block 43 and receives an adjusting screw 55 in a threaded opening. The point of the screw engages with the rear end of the upper block 43 by means of a set screw 56 and a groove 57 in the same manner as the engagement of the adjusting screws 50 with the lower block. These screws 55 are likewise provided with knurled heads 58. The tools 41 are clamped in suitable openings in the upper blocks 43 by set screws 59. The upper blocks 43 are provided with longitudinally extending slots 60 for receiving the clamping bolts 45 and permitting the blocks 43 to be adjusted back and forth.

65 While the belt 17 alone, under usual conditions, is effective for carrying the sleeves around with the drum 20 and trimming the edges of the flanges, it has been found advantageous to provide positive means of driving the sleeves around. This means consists of radially projecting pins 61, prefer-

ably four thereof. These pins project radially from the cylindrical face of the drum 20 and are arranged at the middle of the length thereof. The pins 61 are mounted in radial holes 62 in the drum 20 and are held in place by nuts 63, the inner ends of the pins being enlarged. The pins are yieldingly held projected by light coiled springs 64 in the holes 62 beneath the heads of the pins.

When a sleeve is placed upon the drum to be fed through the machine, the drive pin or pins which may happen to be beneath the sleeve are pushed back into the drum and the next pin behind the sleeve engages the rear edge of the sleeve and pushes it around with the drum. It is understood that during this operation the belt 17 holds the sleeve pressed against the drum. While it is possible that the sleeves, after passing around the drum, would fall off, it has been found best to provide a positive throw-off or stripper. This stripper consists of a yoke 65 made up of a cross or stripper bar 66 which extends longitudinally with the drum 20 and arms 67 which are arranged between the ends of the drum 20 and the brackets 3 and are loosely mounted on the drum shaft 13. The yoke 65 is yieldingly held at the lower limit of its movement by light coiled tension springs 68 which engage at one end with the bar 66 and at their other ends with pins 69 projecting in from the brackets 3. In this lower position, the stripper bar 66 is in the path of the forward edges of the sleeves as they pass around with the drum 20. When the sleeves engage the stripper bar 66, the yoke swings upwardly until the arms 67 contact with inwardly projecting stop pins 70 on the brackets 3. The yoke is stopped by the pins 70 and the further rotation of the drum 20 causes the rear edge of the sleeve to be forced away from the drum, and the portion of the belt 17 extending between the drum 20 and idler pulley 16 carries the finished sleeve away from the drum.

In Fig. 10 there is illustrated one of the flanged harder metal backs 33. In forming these backs out of sheet metal the outer or circumferential edges 71 are apt to be not exactly true to form or dimensions, and in Figs. 7 to 9 inclusive there is illustrated a modification of the machine especially adapted for grinding these circumferential edges 71.

Instead of the cutters 41 grinding wheels 72 are used for this purpose. These wheels are rigidly mounted on a transverse shaft 73 which in turn is rotatably mounted in journal brackets 74 one at each side. The brackets 60 are adjustably mounted on the inclined frame sides 39 and are held in adjusted position by bolts 75. The bases 76 of the brackets 74 are slotted as shown at 77 to receive the bolts 75 and the frame is provided with spaced holes 78 to receive the bolts 75 and they are so ar-

ranged that when the brackets have been adjusted in one direction as far as possible the bolts 75 can be removed and entered into other holes 78. Allowance is made for the reduction of the wheels of about an inch in radius before they need to be replaced. The wheels 72 are spaced on the shaft 73 by suitable collars and sleeves which can be changed to properly space the wheels for grinding the edges of the flanges on sleeve backs of differing dimensions.

Each bracket 74 is provided with an adjusting screw 79 which is rigidly mounted on the frame of the machine and extends through an opening in the bracket parallel with the base. The bracket has an opening for receiving an adjusting nut 80 inserted in the slot 79 so that by rotating the nut 80 the bracket can be advanced or withdrawn, the base bolts 75 being loosened at this time.

The flanges 35 are usually about one-eighth of an inch thick and the wheels 73 are preferably about one inch thick and provision is made for moving the wheel shaft 73 endwise back and forth to equalize the wear on the wheels 72 and preserve the faces straight.

This shaft moving means consists of a bell-crank 81 arranged substantially horizontally and pivotally mounted at its elbow on a pivot bolt 82. The bell-crank 81 consists of an upper and a lower member each having a long arm 83 and a short arm 84. The pivot bolt 82 is secured on a bracket 85 which projects out from the frame of the machine. The bracket 85 is provided with a slot 86 extending longitudinally of the machine, and the pivot bolt 82 with the elbow of the bell-crank 81 can be adjusted to retain its relation with the shaft 73 as the shaft 73 is adjusted to compensate for the wear of the grinding wheels.

The two members of the bell-crank 81 are spaced apart vertically to receive between them a spacer bar 87 clamped tightly between the bell-crank members and which carries rotatably mounted in a slot therein an anti-friction roller 88 for contact with a heart-shaped cam 89 mounted on the shaft 13, which carries the drum 20.

A light tension spring 90 holds the roller 88 against the cam 89. The spring 90 is attached to the free end of the short arm 84 of the bell-crank and to the frame of the machine.

Upon the shaft 73 there is secured a grooved ring 91 and the short arm of the bell-crank engages with a ring 92 arranged in the groove of the ring 91. To effect this engagement threaded pins 92' are provided which project through the upper and lower members of the bell-crank and enter into sockets or holes in the ring 91. The ring 91 is secured tightly upon the shaft and the oscillating movement of the bell-crank im-

parted by the cam 89 moves the shaft with the grinding wheels 72 back and forth.

The shaft 73 may be driven by any suitable means, preferably at high speed. For this purpose there is illustrated a coupling 93 for connecting the shaft 73 to a source of power.

It will be understood that the action of the drum 20 and belt 17 is the same whether the de-burring tools 41 are used to remove the surplus Babbitt metal or the grinding wheels 72 are used to true the edges of the flanges of the blank backs.

As many modifications of the invention will readily suggest themselves to one skilled in the art we do not limit or confine our invention to the specific details of construction or arrangement of parts herein shown and described.

We claim:

1. In a machine of the kind described having a bearing sleeve driving drum and a belt conveyor cooperating therewith, a knock-out device pivotally mounted to swing concentric with the drum and to be engaged by a bearing sleeve as it emerges from between the drum and belt, and stop means for limiting the swinging movement of the knock-out device.

2. In a machine of the kind described having a drum for receiving a bearing sleeve to be trimmed, a driving abutment mounted on the drum and adapted to engage the rear edge of a sleeve to cause it to be carried around by the drum, and means for yieldingly holding the abutment out in sleeve engaging position.

3. In a machine of the kind described having a drum for receiving a bearing sleeve to be trimmed, a plurality of bearing sleeve engaging abutments mounted on the drum and spaced around the same, means yieldingly holding the abutments in bearing engaging position and permitting them to be pushed in, flush with the surface of the drum.

4. In a machine for trimming the outer edges of the flanges of half-cylindrical flanged bearing sleeves, a rotatable drum for receiving the sleeves and with which the sleeves are rotated, a shaft on which the drum is rigidly mounted, a tensioned endless belt trained around the drum and between which and the drum the sleeves are held and carried, a driven pulley around which the belt is trained, a shaft on which the pulley is rigidly mounted, a driving shaft, the driving shaft pulley shaft and drum shaft each carrying a sprocket wheel fixed thereon and a driving chain trained around the several sprocket wheels and by means of which the belt and the drum are simultaneously directly driven at substantially the same surface speed.

5. A machine as defined in claim 4, and including cutters having divided V-shaped operating ends, and screw means for accurately

setting the cutters to trim both edges or corners of both flanges of sleeves passed through the machine.

6. A machine as defined in claim 5, and relatively stationary tools for scraping the edges of the flanges of flanged bearing sleeves as the sleeves are carried around by the belt and drum, the cutting edges of the tools being arranged to engage the flanges at substantially the mid-point of the engagement of the belt with the drum.

In testimony whereof, we have hereunto set our hands this 11th day of May, 1929.

HENRY L. JOHNSON.
BERGER STOCKFLETH.
